DISPENSING APPARATUS

Filed Aug. 13, 1927

Richard C. Wolfe,

INVENTOR

BY *Victor J. Evans*

ATTORNEY

P. J. Hickey.

WITNESS:

UNITED STATES PATENT OFFICE

RICHARD C. WOLFE, OF BEVERLY HILLS, CALIFORNIA

DISPENSING APPARATUS

Application filed August 13, 1927. Serial No. 212,768.

This invention relates to dispensing apparatus primarily designed for use in conjunction with condiment holders to dispense a predetermined quantity of the condiment holder's contents.

Another object of the invention contemplates a measuring device automatically operable to discharge a given quantity when the container is called into use.

10 A further object of the invention comprehends a baffle member carried by the measuring device by means of which further egress of the contents of the container will be prevented other than the capacity discharge of 15 the measuring device.

More specifically stated the measuring device is provided with a handle member in order that several quantities may be discharged from a given position.

20 With the foregoing and other objects in view, the invention further consists of the following novel features and details of construction, to be hereinafter more fully described, illustrated in the accompanying 25 drawing and pointed out in the appended claim.

In the drawing:

Figure 1 is a transverse sectional view taken on line 1—1 of Figure 2.

20 Figure 2 is a sectional view taken on line 2—2 of Figure 1 and illustrating the relative position of the measuring device therein.

Figure 3 is a perspective of the measuring device per se.

35 Figure 4 is a top plan view of the invention.

Referring to the drawing in detail, where in like characters of reference denote corresponding parts, the reference character 10 40 indicates a container or condiment holder, the neck of which is reduced and tapped to accommodate the flange portions 11 of a closure cap 12. The closure cap is provided with an opening 13 from which is struck a 45 curved wall 14, the purpose of which will be presently apparent. Eyes or bearing loops 15 struck or otherwise provided upon the upper side of the closure cap 12 are adapted to accommodate the respective ends of a trun- 50 nion 16.

Semi-circular baffle plates 17 obliquely disposed from the trunnion 16 are projected appreciable distances below the closure cap 12 and within the receptacle or condiment holder 10. One of the plate members 17 is 55 normally positioned in juxtaposition to the inner end of the curved plate 14 struck from the closure cap 12 in the manner as best illustrated in Figure 1 of the drawing.

As illustrated in Figure 2 of the drawing, 60 the plate 14, which provides a working face for the baffle plates 17 is curved both longitudinally and horizontally to conform to the configurations of the respective baffle plates 17. It will be noted that the baffle plates are 65 normally positioned in the manner as illustrated in Figure 1 of the drawing. When the receptacle 10 is called into use, the same is elevated or tipped an appreciable distance to allow the contents of the receptacle to 70 flow toward the baffle plate 17. The pocket as formed between the inner sides of the respective baffle plates 17 is equivalent to that of a teaspoonful or the like. When the receptacle is tipped or tilted an appreciable 75 distance the same, due to the contents of the enclosure thereof, will swing upon its trunnion to occupy the dotted line position in Figure 1 of the drawing whereby the capacity of the enclosure will be discharged and 80 further egress of the contents of the receptacle will be restricted by the innermost of the baffle plates.

It will thus be noted that the device is 85 automatic in operation.

In the event several quantities of the contents of the receptacle are desired to be discharged, an operating lever, such as indicated at 18 provided with ears 19 and carried by one of the baffle plates 17, is engaged by the 90 fingers of the user to manually operate the measuring device whereby the necessity of successively altering the position of the receptacle is not incumbent upon the user.

Although I have shown, described and illustrated the invention as being designed for application upon a receptacle of the character described it is to be understood that I do not limit myself to the employment of the invention but that the same may be effectively 100

applied in the dispensing of the various sorts of merchandise.

6 A guard, such as indicated at 20, upstanding from the straight edge of the opening 13, is primarily designed to overlie the intersecting portions of the baffle plates 17 and to prevent spilling of the contents of the holder when the latter is reversed in dispensing position.

10 The invention is susceptible of various changes in its form, proportions and minor details of construction, and the right is herein reserved to make such changes as properly fall within the scope of the appended claim.

15 Having thus described the invention what is claimed is:—

19 A dispensing apparatus comprising a receptacle having a closure cap, a plate struck from the top of the cap being adapted to provide a discharge port, said plate being bent upon itself to provide a curved inwardly projected wall, eyes struck and upstanding from the upper side of the closure cap adjacent one side of the discharge port, a trunnion having 25 the extremities thereof journaled within said eyes, baffle plates obliquely and oppositely projected from the trunnion being adapted for cooperation with the curved wall to measure and discharge a predetermined quantity 30 of the contents of the receptacle, and an operating lever carried by the baffle plates and projected through the discharge port and which terminates to provide finger engaging portions upon the extremity thereof.

35 In testimony whereof I affix my signature.
RICHARD C. WOLFE.
